COMBINATION BRUSH AND AEROSOL DISPENSER

Daniel H. Gattone, Drexel Hill, Pa., assignor to Birch & Gattone, Washington, D.C., a partnership

Filed Oct. 11, 1963, Ser. No. 76,941

Term of patent 14 years

(Cl. D9—2)

The dominant features of my design reside in the portions shown in full lines.

I claim:

The ornamental design for a combination brush and aerosol dispenser, as shown and described.
